United States Patent Office

Des. 184,075
Patented Dec. 9, 1958

184,075

UTILITY TRAY

Earl S. Tupper, Smithfield, R. I., assignor to Tupper Corporation, North Smithfield, R. I., a corporation of Delaware

Application October 17, 1957, Serial No. 48,142

Term of patent 14 years

(Cl. D44—10)

Fig. 1

Fig. 2

Fig. 3

Figure 1 is a view in perspective of a utility tray, embodying my new design;

Figure 2 is a top plan view thereof; and

Figure 3 is a side view in elevation.

I claim:

The ornamental design for a utility tray, substantially as shown.
